WEARING APPAREL

Inga Carlen Allen, Wilkinsburg, Pa.

Application February 3, 1938, Serial No. 188,477

1 Claim. (Cl. 36—2)

This invention relates to leggings for protecting the leg of the wearer from rain, accidental splashing, wind and cold, and is particularly applicable for wear by women.

5 It is an object of my invention to provide a legging which is waterproof to the extent that it will protect the leg and foot of the wearer against rain or splashing, is slightly when worn, and which is exceedingly thin so that it can be 10 folded compactly and carried about without inconvenience and will be available for emergency use.

15 A further object is the provision of a legging of thin, transparent, waterproof material which provides an insulating layer of air between the legging and the leg of the wearer to protect the wearer against cold, and which is adequately ventilated to prevent condensation of moisture therein.

20 Still another object is the provision of a legging of thin, transparent, waterproof material which loosely drapes about the leg of the wearer and is held substantially out of close contact therewith to provide an insulating layer of air 25 between the legging and leg.

A further object is the provision of a legging of thin, transparent, waterproof material having an elastic band at the top which supports the legging on the leg of the wearer and which holds 30 the legging in folds to keep it substantially out of close contact with the leg of the wearer.

These and other objects of the invention will be apparent from a consideration of the following description taken in connection with the annexed drawing, wherein I have shown preferred embodiments of my invention by way of example and wherein:

Figure 1 shows the legging applied to the left leg of the wearer.

40 Figures 2, 3 and 4 show respectively the development of the front outside, inside and rear outside sections respectively of the legging before being assembled.

45 Figure 5 shows the auxiliary fastening means at the top.

Figure 6 is a section taken on line VI—VI of Figure 1, showing the manner of securing the slide fastener tape,

50 Figure 7 is a section on line VII—VII of Figure 1, showing the manner of finishing the top corners,

55 Figure 8 is a section on line VIII—VIII of Figure 1, showing the manner of finishing the bottom edge and securing the heel strap.

Figure 9 is a fragmentary view showing a modified top construction.

Figure 10 is a section taken on line X—X of Figure 9.

Figure 11 shows a modified stitching for sewing the legging sections together.

Figure 12 is a container for holding the legging, and

Figure 13 is a modification illustrating a ventilating means.

Referring to the drawing, the legging is made up of an inside piece 1, the longitudinal edges 2 and 3 of which are curved, a front outside piece 4 having one substantially straight edge 5 and a curved edge 6, and a rear outside piece 7 having a straight edge 8 and a curved edge 9. The sections 1, 4 and 7 preferably are made of oiled silk which is pliable, transparent and waterproof.

However, any other suitable transparent waterproof material, such as balloon silk, Cellophane, or the like, may be employed. If desired, the material may be colored as well as transparent. Slits 10 are provided adjacent the top, and the legging sections are assembled by securing together the edges 6 and 2 and edges 3 and 9, by sewing, by adhesive, or in any other suitable manner, to form any desired type of seam. The bottom of the legging is formed so as to have a heel covering portion 11 and an instep covering portion 12, the end of the instep covering portion 13 being preferably angular as indicated at 13, to have it conform better and lie more smoothly on the instep of the wearer and vamp of the shoe.

Preferably the bottom edge 14 of the legging is reinforced by a woven tape 15 which is folded over the edge 14 and sewed by stitches 16 (Figure 8) so as to protect the raw edge against tearing or being pulled out of shape. A strip of fabric or tape 17 is sewed by stitches 18 to the heel covering portion on inside section 1 and outside section 7 and serves as a heel strap passing under the shank 19 of the shoe to hold the legging in close contact with the counter of the shoe. If desired, this heel strap 17 may be made adjustable, and is made of material that is easily cleaned, such as silk, oiled silk or the like.

The strap 17 preferably is made of tape wrapped in oiled silk so that it will not absorb water and will not become easily soiled.

The vertical margins of the legging preferably are secured in closed position by completely separable slide fasteners which are commercially available mounted on tapes. When the oiled silk used for the legging is clear, white slide fasteners preferably are employed. However, with col-

ored materials, correspondingly colored slide fasteners may be used. The tape 21 of one fastener 22 is secured to the straight longitudinal edge 5 of the front section preferably by doubling the silk near the edge as indicated at 23 (Figure 6) and bringing the loose end of the silk around to the other side of the tape as indicated at 24, and passing stitches 25 through the tape and the three thicknesses of silk. Preferably one edge 26 is left as a flap to underlie the slide fastener to protect the stocking against snagging by the metal of the fastener, the flap being used only on one of the fastener tapes. If desired, this flap may be doubled back with the raw edge 15 turned under so that it will be caught by the stitches 25. The flap is made wide enough to prevent being caught by the hand grip 30 of the slide fastener. The other tape 27 of the fastener strip 28 preferably is secured in a similar manner 20 with the raw edge of the silk turned under, but the flap in this case may be omitted. The lower corners are finished by sewing the bottom tape 15 over the slide fastener tape.

The upper edge 29 of the assembled legging is turned over a strip of elastic material 31 (Figure 25 7) and sewed at 32 with the raw edge 29 turned under. Any suitable elastic material, such as a fabric having a warp of rubber bands may be used. Preferably the band 31 is shorter than the 30 top circumference of the legging and is stretched to the circumference of the legging and sewed while thus tensioned. The tension on the elastic band then is removed so that it returns to its normal length and thus gathers the top of the 35 legging. It will be understood that the legging is made of sufficient circumference at the top so that even when the elastic band is stretched, as in wearing, the legging will be gathered at the top as indicated at 33 and held substantially out 40 of close contact with the leg of the wearer. The folds at the top of the legging assist in holding the silk out of contact with the leg of the wearer and the slits 10 at the top provide ventilation to prevent condensation of moisture within the legging. These slits preferably are located above the dress line and in the folds of the legging adjacent the top band, so that the folds of the legging keep the slits gaping to improve the ventilation. This construction has the advantage that 45 50 the slide fastener tapes are covered by waterproof material and thus will not become wet when the legging is worn.

A hook 35 (Figure 5) is secured adjacent one end 36 of the top elastic band 31 and an eye 37 is sewed to the other end 38 of band 31, the end 38 being allowed to extend far enough to protect the stocking of the wearer from contact with the hook 35.

It will be understood that the legging for the 60 right leg is constructed exactly like that for the left leg, with the slide fastener on the outside. The legging is applied by first inserting the heel in the heel strap 17, securing the hook 35 in the eye 37 at the top, then pulling up the slide fastener by 65 the grip 30 to the top. The seams between the sections of the legging occur at the front and back, and the slide fastener tapes are substantially straight and vertical and do not tend to pull the legging out of shape. Although the legging is 70 loosely fitting it is not unsightly because the outline of the leg visible therethrough predominates. Ventilation is improved by having the legging lie

loosely over the vamp of the shoe. Preferably it is held tightly over the counter of the shoe, at which point the most splashing generally occurs.

In the preferred construction shown, the legging is of continuous waterproof transparent material, there being no elastic or textile material between the sections which allows water to soak through. All parts of the legging are waterproof excepting for a very small portion of the slide fastener tape, which, however, has a flap of oiled 10 silk underneath so water cannot penetrate to the leg of the wearer. Consequently the legging can be wiped dry after use, or can be hung up to dry by evaporation. The legging has no bulky parts and can be folded and placed in a bag 15 20 25 of waterproof material such as oiled silk, especially when it is wet after use, tied in by the tapes provided, and carried in a woman's purse available for emergency wear. The bag 40 need not be larger than about three by four inches and, after being tied and folded over with a pair of leggings therein, does not occupy more than about three by two and a half inches, and is about one inch thick at the thickest portion of the package.

In a modification, the bottom of the legging 25 may be finished by folding the silk over a strip of tape, tucking under the raw edge, and stitching the parts together substantially as shown in Figure 7, the tape preferably being non-elastic. This construction has the advantage that the edge is 30 reinforced and no part of the tape is exposed and therefore the tape cannot become wet.

In a further modification (Figure 10) an elastic band 41 is secured to the top by folding a band 42 of tape over the upper edge 29 of the 35 legging, interposing the elastic band 41 in stretched condition between the tape and silk, and sewing the parts together, the stiches 44 passing through the silk, elastic band and tape. The tension on the band then is removed so that 40 the legging is gathered at the top. The legging is made sufficiently wide at the top so that the gathered portion is held substantially out of close contact with the leg. This construction has the 45 advantage that the silk passing around the band at the top is prevented from contacting the leg of the wearer.

In Figure 11 I have shown a type of stitch known as the Merrow stitch which may be used for sewing together the sections of the legging, 50 if desired. In Figure 13 I have shown punched holes 46 instead of slits for ventilation, the holes preferably being in the gathered portion of the legging.

It will be understood that various modifications 55 may be made without departing from the spirit or scope of the invention.

I claim as my invention:

A legging of thin transparent waterproof sheet material shaped to generally conform to the leg 60 of the wearer and adapted when worn to conform loosely to the leg of the wearer, an elastic member gathering the legging at the top to support the upper margin on the leg of the wearer, apertures in said legging below the top, and a lower portion 65 adapted to overlie the vamp and counter of the shoe of the wearer, said lower portion providing a loose fit to allow circulation of air through the legging whereby condensation within the legging is substantially prevented.
